Des. 183,727

Patented Oct. 21, 1958

183,727

COMBINED BELT BUCKLE, BOTTLE OPENER, AND CAN OPENER

Odie D. Emberton, Fort Worth, Tex.

Application April 22, 1955, Serial No. 35,642

Term of patent 14 years

(Cl. D17—1)

Fig. 1.

Fig. 2.

Fig. 3.

Fig. 4.

Figure 1 is an edge view of a combined belt buckle, bottle opener and can opener, showing my new design;

I claim:

The ornamental design for a combined belt buckle, bottle opener, and can opener, substantially as shown.
